UNITED STATES PATENT OFFICE.

JAMES WARD, OF BOSTON, MASSACHUSETTS, ASSIGNOR TO HIMSELF AND ISAAC F. HUNNEWELL, OF SAME PLACE.

IMPROVEMENT IN BRICK-MACHINES.

Specification forming part of Letters Patent No. 36,690, dated October 14, 1862

To all whom it may concern:

Be it known that I, JAMES WARD, of Boston, in the county of Suffolk and State of Massachusetts, have invented an Improved Brick-Machine; and I do hereby declare the same to be fully described in the following specification, and illustrated in the accompanying drawings, of which—

Figure 1 is a top view; Fig. 2, an end elevation; Fig. 3, a central and vertical section; Fig. 4, a side view of one of the inclines or eccentrics for raising and depressing the sliding bottom of the brick-matrices. Fig. 5 is a side view of one of the sliding bottoms of such matrices.

The object of my invention is to produce a simple and efficient machine which will mold the clay in a comparatively dry state, so as to make what are technically called "pressed brick."

In the drawings, A denotes a rectangular frame, which is supported upon two angles by means of four wheels, B B B B. On the top plate of the said frame, and near its center, a circular table, C, is firmly secured by means of screws, or in any other suitable manner.

D is the pug-mill, which is arranged on one side of the machine E, being the hopper thereof. The front end of the said mill is supported by an arched frame, F, extended upward from the frame A and secured thereto, as seen in the drawings, the rear portion being supported by a plate or bar, W, extending upward from the circular table C. The said pug-mill is of a rectangular shape, and has two shafts, G H, extending horizontally through the lower part of the frame and carrying two large drums or rollers, I I, which serve not only to pulverize or reduce the clay, but also to crowd and compress such clay into the molds. On each of the outer ends of the shafts G H there are gear-wheels K K', which mesh into each other, and beside the said gear K engages with a pinion, L, which in its turn engages with a large pinion, M, carried by a shaft, N, which is supported by the frame A. The said shaft N carries a small pinion, O, which operates in conjunction with an endless rack, U, disposed as seen in Fig. 6, which is an under side view showing the rack and pinion.

P is a circular matrix plate or bed, which is arranged horizontally and has its lower edges resting on the top of the frame A. The top surface of the said plate P should come up flush with the lower surface of the grinding and compressing rollers I I. Furthermore, the said bed-plate has two concentric rows of brick-matrices, Q Q Q, &c., formed vertically through it, each of which is rectangular in cross-section and of the size of the bricks to be molded. Each of the said matrices is provided with a sliding bottom, R R R, &c., a side view of one of which is given in Fig. 5. The said plungers or sliding bottoms are each formed with a slot, b, in its lower end, which is made to straddle a circular stationary rail, S or S', having two flanges extending from it on opposite sides. The legs O O' of each of the sliding bottoms are so formed as to extend underneath each of the flanges; and, furthermore, the said flanges are formed as inclines, so as to properly guide the plungers in their vertical movements—that is, so that they shall be at their lowest point of depression when the matrices come directly under the rollers I I, and shall be at their highest elevation or flush with the top of the bed-plate for about sixty degrees in a direction opposite to that of the mill, the same being for the purpose of allowing the brick to be taken from the table. The inner row of matrices is formed like the outer one, and has its plungers made in like manner and applied to the stationary rail S', so as to operate like them, the said rail being formed with flanges, and with inclines like those of the rail S. T is the striker or smoother, which serves to strike off the surplus amount of clay and smoothen the tops of the bricks, the same being arranged on one side of the mill, as seen in the drawings.

Having described the construction of my machine, I will describe its operation.

If we suppose the driving-shaft G to be put in rotation by any suitable motor, the train of gears K, K', L, and M will be put in revolution, and will not only impart motion to the reducing and pressing rollers I I, but to the shaft N, which carries the pinion O. Such pinion engaging with the endless rack U will give a continuous rotary motion to the circular matrix or wheel P, whereby each of the ma-

trices of the two series of matrices will be brought consecutively under the pug mill, and as the mill or the hopper is supposed to be filled with clay the said rollers I I will not only properly reduce the clay, but will force it down into the molds and compress it therein as they come underneath them, (the said rollers). As fast as the molds become filled, they are carried forward under the striker T, which removes the surplus clay from them and smoothes the top of the clay in such molds. The molded bricks being carried forward by the rotation of the bed or matrix plate, are forced up out of their matrices by means of their plungers or sliding bottoms acting upon the inclines or eccentric rails S S', and remain on a horizontal line with the bed for about one-third of the circle of revolution. The bricks must be taken away during their passage through such arc of the circle, for, as they be-

gin to approach toward the mill again, the inclines cause such sliding bottoms to gradually fall until again near the mill, where they will have reached their lowest point of depression, when, should they be empty, they will be again filled and operate as before.

I do not claim the invention as shown and described in the application of Waldron Beach, withdrawn April 10, 1841; nor do I that as shown and claimed in Patent No. 23,892; but

What I claim is—

The arrangement of the pulverizing and pressing rollers I I, in combination with the revolving series of molds, when geared and operated conjointly, in the manner and for the purpose specified.

JAMES WARD.
